SKELETON FRAMEWORK STRUCTURE AND
METHOD OF CONSTRUCTING THE SAME

John B. Goldsborough, Croton on Hudson, N. Y.

Application June 1, 1935, Serial No. 24,532

6 Claims. (Cl. 61—44)

This invention relates to the construction of buildings and other structures by the use of vertical beams of steel or other suitable material serving both as temporary and permanent foundation piles and permanent structural columns, as well as providing temporary lateral support for the sides of the substructure excavation and/or exposed adjacent structures.

With the present method of design and construction of buildings and other structures requiring pile foundations, considerable delay occurs in the erection of the structural steel framework due to the necessity of installing, complete, each pile foundation pier before its column is erected. It is an important object of this invention to provide for reducing such delay, as by enabling the structural steel framework erection to be started before the completion of the pile installation.

With the present method of construction expensive shoring or cross-lot bracing is required for the temporary lateral support of the earth sides of the substructure excavation, and/or adjacent exposed structures. It is therefore another object of this invention to eliminate this expensive shoring or cross-lot bracing by utilizing the more rapid installation of the permanent flooring system to provide lateral support for the adjacent sides by means of vertical beam wall piles driven before excavation has proceeded.

A further object of this invention is to eliminate the necessity for expensive temporary support of a working platform at street level when the foundations under construction are for the support of a building, by utilizing the more rapid installation of the permanent flooring system as a support for a working platform to carry on the usual operations involved in the installation of the permanent pile foundations and basement excavation.

Other objects and advantages of this invention will become apparent from the following description of preferred embodiments illustrated by the accompanying drawings, in which like reference characters designate like parts in the several views:

In the drawings:

Figure 1 illustrates in perspective view one method of installing the structural steel flooring system at street level, prior to the installation of permanent pile foundations, or of the completion of basement excavation;

Figure 2 illustrates in cross section the process of basement excavation after the installation of

permanent pile foundations and erection of the structural steel framework;

Figure 3 illustrates in longitudinal elevation the lateral support of the earth sides below an existing building wall;

Figure 4 illustrates in cross sectional plan the lateral support of the earth sides under the existing building wall shown in Figure 3;

Figure 5 illustrates in cross sectional plan one method of lateral support for an existing building wall;

Figure 6 illustrates in cross sectional plan one method of reinforcing a steel beam master column-pile with two additional steel beams;

Figure 7 illustrates in elevation one method of load distribution from the steel beam master column-pile to permanent I-beam pile foundations;

Figure 8 illustrates in cross sectional plan the method of load distribution shown in Figure 7;

Figure 9 illustrates in perspective elevation one method of lateral support for the earth sides of substructure excavation;

Figure 10 illustrates in cross section one method of lateral support for the earth sides of substructure excavation in wet or heavy soil;

Figure 11 illustrates in perspective view the method of lateral support for the earth sides of sub-structure excavation shown in Figure 10;

Figure 12 illustrates in sectional plan one method of supporting the earth sides in Figures 10—11 by means of a vertical steel beam column-pile and steel sheet piling;

Figure 13 illustrates in perspective view one method of installing a temporary decking for use in the so called "cut and cover" method of excavation usually employed in the construction of subways and other underground passages under roadways which must be kept open for traffic;

Figure 14 illustrates in cross section a structural design for a subway or other underground structure, embodying one method of support for a temporary decking shown in Figure 13, and lateral support for the earth sides of the excavation;

Figure 15 illustrates in cross section one method of support for a temporary decking shown in Figure 13;

Figure 16 illustrates in cross section a structural design for a subway, or other underground structure, embodying one method of support for a temporary decking, vertical support of an adjacent building, and lateral support of the earth sides; and

Figure 17 illustrates in elevation a structural design for a subway or other underground structure, embodying one method of support for a temporary decking and lateral support for the 5 earth sides of the excavation, all as shown in Figures 13-14-15-16.

Referring to Fig. 1, vertical steel beam master column-piles 20 and intermediate vertical steel beam wall piles 21 have been driven and structural steel beams 22, included in a flooring system, which may be substantially at street level, have been installed. The structural steel flooring system provides lateral support necessary for excavation for a substructure or basement, thus 10 enabling the omission of expensive cross-lot bracing and temporary working-platform supports. Furthermore, the steel floor beams 22 at all 15 sides of the frame near the ground level may be used to connect the upper ends of the intermediate piles 21 with the master column-piles 20. It will be evident that, beneath the street level floor system, the piles 20 and 21 may be supported 20 against outside lateral pressure as by engagement of their lower parts with earth into which they have been driven. The installation of the vertical steel beams may have been effected by driving them vertically into the ground as described 25 in the United States patent to John B. Goldsborough, No. 1,895,985, issued January 31, 1933.

According to the showing in Fig. 1, a new building is in course of construction between walls 23 and 24 of adjoining existing buildings and excavation has just been started. Further 30 excavation may be carried on in any desired 35 manner, as for example as shown in Fig. 2 where a decking installed by placing heavy decking member 25, such as wooden beams on the steel floor beams 22, is used to support a portable derrick 26 for operating a clam-shell bucket 27 40 through openings in the decking obtained by removing decking members 25 at the desired positions.

As illustrated in Fig. 2, the wall 23 of one adjoining building is supported on pile foundations, comprising piles 28, and the basement portion 45 of the wall 23 is of sufficient depth as not to be affected by the basement depth of the building under construction. The wall 24 of the other adjoining building is shown as supported 50 on spread footings 29 at a higher level than the basement depth of the building under construction. In this case the foundation of the wall 24 is carried down to undisturbed soil by means of 55 concrete underpinning piers 30 joined to the vertical steel beam piles 20 and 21 as shown in Figs. 3 and 4. Opposite the walls of adjoining buildings, no lateral support is needed, unless by blocks 30a and wedges 30b (Figs. 2 and 5), and consequently no sheeting is ordinarily required.

Where the sides of the substructure excavation 60 are of earth as illustrated in Fig. 9, lateral support for such earth sides may be provided by means of a retaining wall formed of horizontal sheeting members 31 placed outside the vertical 65 steel beam piles 20 and 21 as the excavation proceeds and depending upon these steel beams for lateral support. The beam-piles 20 and 21 are obviously driven prior to excavation and the intermediate beam-piles 21 are secured, after 70 installation, to the corresponding horizontal steel beam members 22 of the permanent framing or flooring system, extending between steel beam master piles 20, by suitable connections. Additional sheeting members 31 are placed in position 75 outside of the piles 20 and 21, as the excavation

is continued downwardly, whereby the earth sides receive lateral support from the permanent structural system comprising the framing or flooring system, the beam piles and the sheeting, and expensive temporary shoring or cross-lot bracing 5 is unnecessary. This method employing horizontal sheeting is adaptable to excavation in dry or de-watered soil.

If the substructure excavation be made in wet or very heavy soil, lateral support for the earth 10 sides is preferably effected by use of vertical interlocking steel sheeting 32 and wales 33, as illustrated in Figs. 10, 11 and 12, and hereinafter described in connection with these figures.

In many cases the master column-piles 20, if 15 driven to refusal, have sufficient bearing value in themselves to provide permanent support for the entire structure, and the foregoing description has been given as if this were the case. However, if required, additional bearing value 20 may be given to a master column-pile 20 in any suitable manner, as for example by the attachment thereto of additional beams 34 in the manner illustrated in Fig. 6 and at the right in Fig. 2.

Where the bearing value of a column-pile 20 25 is sufficient for the temporary load but not for the permanent load, the load may be transferred to a suitable permanent foundation such as illustrated in Figs. 7 and 8 and at the middle of Fig. 2. Such permanent foundation may comprise piles 30 35 of suitable form, for example steel beam piles, driven after the master column-pile 20 has been installed and the column load may be transferred to them in any suitable manner as by means of cap pieces 36 in the form of channels, wedged 35 grillage beams 37 supported on the piles 35, column brackets 38, which may be in the form of short beams riveted to the column-pile 20, and wedges 38a.

In Figs. 10, 11 and 12, there is illustrated a 40 type of construction for a subway, or other underground passage structure by the so-called "cut and cover" method. In this case the excavation is to extend only part way across the roadway and the necessary part of the roadway paving 45 is removed leaving the sidewalk 40 intact, the building wall 41 and its footing 42 being sufficiently distant from the excavation to avoid disturbance under ordinary conditions.

Vertical steel beam column piles 20a are driven 50 into the ground prior to general excavation and, at each side of the excavation, the upper ends of as many of these piles as desired are capped by suitable members 43, such as continuous horizontal steel channels, serving to support steel decking beams 44 of a temporary decking which 55 also includes heavy decking members or beams 25, such as shown in Fig. 2. By removing the beams 25 in any desired location, the work of excavation may be continued at that location 60 without material interference with the use of the street. The metal sheeting members 32 may be driven substantially at the same time as the column-piles 20a and at such a distance therefrom that, as the excavation is carried down, horizontal beams or wales 33 may be inserted 65 between member 20a and the sheeting 32 to provide lateral support therefor. Fig. 12 shows these vertical steel beam wall column-piles 20a as forming an integral part of the permanent subway, 70 or other underground passage structure (usually comprising concrete) serving not only as sidewall columns for lateral support of the earth sides and vertical support of the underground structure roof, but also as permanent pile foundations 75 for vertical support of the underground structure 71

wall. The vertical wall column-piles 20a are held against lateral pressure by the installation of the permanent transverse steel beams 22a forming the framework of the structural steel roofing system of the underground structure. The beams 22a are installed prior to the completion of excavation to final subgrade (see Fig. 11) and are secured to the column-piles 20a in any suitable manner.

10. Resistance against lateral movement of the bottoms of the vertical steel beam wall column-piles, prior to the installation of the permanent flooring system, is provided by the insertion of the piles into the earth soil to a suitable depth 15 below the elevation of final excavation subgrade, and additional resistance will be provided by the permanent flooring system, of structural steel and/or concrete. The lateral support provided in this way renders unnecessary the expensive 20 interior longitudinal and transverse temporary bracing of the earth sheeted sides, heretofore used during construction. Thus the erection of the steel framework forming the walls and roof of the underground structure, together with sub- 25 sequent operations necessary for the completion of the structure, can proceed simultaneously with the excavation, thereby reducing the total time required for complete construction of the subway by the time required for completion of excavation 30 from the underside of the roof to final subgrade, which time for excavation would ordinarily elapse before the other construction could be started.

As illustrated in Fig. 11, some of the column-piles 20a may be cut off at the level of the roof beams 22a at the time of installation of the latter, others being left to support the temporary decking. Upon completion of the roof structure and removal of the temporary decking, the upper ends 40 of the column-piles used to support the decking may be cut off.

Another very great advantage of this type of construction is that the utilities, such as water mains, sewers, gas mains, electrical conduits and the like, can be permanently restored or relocated while the excavation of the subway is carried on. Obviously this will effect a great saving in view of the fact that such utilities would ordinarily have to be maintained during construction 45 of the subway, or shifted temporarily and permanently located after the completion of the subway.

In Figs. 13 and 14, there is illustrated a type of subway construction similar to that illustrated in Figs. 10, 11 and 12, but varied to meet conditions which involve the removal of all the roadway paving 39 and the sidewalk, and excavation 50 to the foundation of the building wall 41. In this case the decking beams 44 extend to the building walls and are braced against the same by suitable blocking and wedging and are secured to the channels 43, as by bolts, to assist in holding the tops of the column-piles 20a against lateral movement. As illustrated in Fig. 55 13, louvred sheeting 45 is installed against the outside faces of the column-piles 20a as excavation proceeds. The roofing beams 22a, when installed, furnish strong lateral support for the upper end of column-piles 20a.

60. Figure 14 illustrates a design and method of construction whereby that portion of the vertical steel beam wall column-piles 20a above the finished roof of the subway, or other underground passage structure, will remain in place 65 at the completion of the work, below the longi-

tudinal steel member 43 under the transverse decking beams, and the concrete masonry wall of the underground passage structure is carried up to the top of the steel beam wall column-piles 20a to form a permanent sidewalk underground 70 vault wall for the adjacent building. Thus with this invention the full length of steel beam wall column-piles 20a forms an integral part of the permanent construction, or reconstruction, involved in the installation of a subway, or other underground 75 passage structure. Additional longitudinal rigidity may be imparted to the vertical steel beam column-piles 20a by means of a continuous steel channel, or other suitable member, placed against the inside faces of the 80 column-piles and the bottom faces of the roofing beams 22a and secured thereto.

Figures 15 and 16 illustrate a design and method of construction similar to that shown in Figure 14, with the exception that the subway, or other 85 underground structure, is located in close proximity to the foundations of the existing adjacent building. In this case the portions of the vertical steel beam wall column-piles 20a above the finished roof of the underground passage structure 90 do not remain in place to form an integral part of the design involved in the construction, or reconstruction, of a permanent sidewalk underground vault wall, but is removed above the top of the permanent underground passage roof, 95 at the completion of the work. In Figure 15 the temporary decking has been installed at street level and vertical steel beam wall column-piles 20a driven into the soil outside the existing spread footings of the building. In this case 100 excavation for the subway, or other underground passage structure, has proceeded only to the depth of the existing adjacent building basement floor and an underpinning pit 46 is in process of installation for the permanent support of the 105 building. In Figure 16 construction has been advanced to the completion of excavation to final 110 subgrade for the subway, or other underground passage structure, and the permanent structural steel roofing system installed. The existing building foundations have been carried down to an elevation below the underground passage structure 115 subgrade by means of concrete underpinning piers 47 installed in sheeted pits. The outlines of the permanent concrete masonry floor, walls, and roof, of the underground passage structure 120 are indicated, the outside face of the walls extending flush to the outside face of the new underpinned foundations of the existing building. Thus it is apparent that permanent lateral support 125 of the reconstruction building foundations, and of the earth soil under the basement floor, is provided by means of the reconstructed foundations and the new underground passage structure. In this case the permanent structure steel 130 roofing system of the underground passage structure has been installed prior to the completion of the general excavation to final subgrade. Thus with this invention temporary lateral support of the existing building is provided by means of the vertical steel beam wall column-piles 20a, suitably 135 wedged and blocked to the existing building; secured at the top to the transverse decking beam and at the bottom by their insertion into the earth soil to a suitable distance below the final 140 subgrade; and with additional resistance to lateral movement provided by the permanent structural steel roofing system of the subway, or other underground passage structure. Thus it is apparent that according to this invention expen- 145

sive temporary shoring, or cross-lot bracing, to prevent lateral movement, as well as expensive temporary vertical supports of the decking to final subgrade elevation, are unnecessary.

5. Figure 17 illustrates the several stages of procedure used during the construction of a subway, or other underground structure, by the so-called "cut and cover" method of excavation under a roadway decked over to maintain traffic. Vertical steel beam wall column-piles 20a have been driven into the soil from the surface and a temporary timber roadway decking installed. This timber decking is supported by alternate vertical steel beam wall column-piles 20a by means of transverse steel beams 44 and longitudinal steel channel members 43. Temporary lateral support of the earth sides of the excavation is provided by the steel beam wall column-piles 20a and horizontal louvered board sheeting 45, with additional 10 rigidity provided by the permanent transverse structural steel roof members 22a installed prior to the completion of excavation to final subgrade.

It should be understood that after the construction of any one of the skeleton framework structures herein disclosed has progressed to a sufficient extent, the structure may be completed with any suitable material, such as concrete which is illustrated in the drawings.

It should be understood that changes may be made in different features and that certain features may be used without others without departing from the true scope and spirit of the invention.

Having thus described my invention, I claim:

35. 1. The method of constructing foundations for a skeleton-framework structure including a substructure, which comprises the installation in the ground of substantially vertical permanent column members of the framework prior to completion of excavation, the installation of permanent foundations adjacent to one of said column members, and the transfer of column load from such column member to said permanent foundations during the construction of said skeleton framework structure above the ground.

40. 2. The method of constructing a skeleton-framework building, which comprises introducing directly into the solid ground substantially vertical permanent column members of such framework including column members arranged at the 45 edges of the area to be excavated, excavating from such area, proceeding with the erection of said

building during excavation, introducing additional substantially vertical members into solid ground adjacent to one of said column members, and transferring load from said column to said additional members.

5. 3. The method of constructing a skeleton-framework building which comprises introducing directly into the solid ground substantially vertical permanent column members of such framework including column members arranged at the 10 edges of an area to be excavated, excavating from said area, proceeding with the erection of said building during the excavation, and increasing the bearing value of the footing of one of said column members by securing thereto beams driven 15 into the ground at the bottom of said excavation adjacent to such column member.

4. In a skeleton-framework structure comprising a substructure in an excavation, substantially vertical permanent column members of said 20 framework extending into the earth at the bottom of the excavation and serving both as piles and structural columns to sustain column loads, column piles in the earth adjacent to one of said column members, and connections between the 25 column piles and such column member to transfer load from the column member to the column piles.

5. In a skeleton-framework structure comprising a substructure in an excavation, substantially vertical permanent column members of said 30 framework extending into the earth at the bottom of the excavation and serving as piles to sustain column loads, column piles in the earth around one of said column members, and connections between the column piles and such column member 35 to transfer load from the column member to the column piles, said connections including brackets on the column member and transverse load-distributing members and wedges interposed between the brackets and the column piles.

40. 6. In subway construction adjacent to buildings, substantially vertical permanent column members, the lower end of each column member providing its own footing to bear its portion in supporting the load of the subway structure, 45 channels at opposite sides of the subway resting on the tops of column members, transverse decking beams resting on said channels and providing lateral support for the wall of said building, and upper decking members extending substantially 50 at right angles to the decking beams.

JOHN B. GOLDSBOROUGH.
